CLAIM

The ornamental design for a modular attachment for scuba instrument case, substantially as shown and described.

DESCRIPTION

FIG. 1 is a top plan view of a modular attachment for scuba instrument case incorporating my new design;

FIG. 2 is a front elevational view thereof;

FIG. 3 is a right side elevational view thereof;

FIG. 4 is a rear elevational view thereof; and

FIG. 5 is a bottom plan view thereof.

The omitted left side elevational view corresponds to the mirror image of FIG. 3.

*Fig. 4.**Fig. 1.**Fig. 2.**Fig. 3.**Fig. 5.*
